POWER-DRIVEN AQUAPLANE

Vincent C. Cipollone, Ridley Park, Pa.

Application April 15, 1954, Serial No. 30,024

Term of patent 3½ years

(Cl. D71—1)

Fig. 1.

Fig. 2.

Fig. 3.

Fig. 4.

Fig. 5.

To all whom it may concern:
Be it known that I, Vincent C. Cipollone, a citizen of the United States, residing at Ridley Park, county of Delaware, Commonwealth of Pennsylvania, have invented a new, original, and ornamental Design for a Power-Driven Aquaplane, of which the following is a specification, reference being had to the accompanying drawing, forming a part hereof.

Fig. 1 is a side elevational view of a power-driven aquaplane embodying my new design;
Fig. 2 is a perspective of the same;
Fig. 3 is a top plan of the same;

Fig. 4 is an end elevation viewed from the stern;
Fig. 5 is an end elevation viewed from the bow.
I claim:
The ornamental design for a power-driven aquaplane, as shown.
